(57) **CLAIM**

The ornamental design for a bottle holder, as shown and described.

DESCRIPTION

FIG. 1 is a front view of a bottle holder showing the new design;

FIG. 2 is a perspective view of the bottle holder;

FIG. 3 is a rear view of the bottle holder;

FIG. 4 is a left side view of the bottle holder;

FIG. 5 is a top view of the bottle holder;

FIG. 6 is a right side view of the bottle holder; and,

FIG. 7 is a left side view of the bottle holder in another position.

The broken lines showing a bottle in FIGS. 1-7 are for the purpose of illustrating environmental structure and forms no part of the claimed design.

1 Claim, 7 Drawing Sheets
